J. G. JACKSON

STEEL TRUSSED STRUCTURE

Filed Feb. 10, 1925

UNITED STATES PATENT OFFICE.

JOHN GRANT JACKSON, OF CHATHAM, ONTARIO, CANADA.

STEEL-TRUSSED STRUCTURE.

Application filed February 10, 1925. Serial No. 8,234.

To all whom it may concern:

Be it known that I, JOHN GRANT JACKSON, a subject of the King of Great Britain, and a resident of the city of Chatham, in the county of Kent, in the Province of Ontario, Canada, have invented certain new and useful Improvements in Steel-Trussed Structures, of which the following is the specification.

10 My invention relates to improvements in steel trussed structures and the object of the invention is to devise a steel structure stiffened and reinforced by a cementitious material in such a manner as to increase the 15 strength of the structure under compression strains to be at least equal to the tensile strength of the steel.

A further object is to construct a cement reinforced steel structure which will have 20 less tendency to deflect or buckle under compression due to transverse or bending stresses as a result of the greater spacing of the active elements and consequently greater 25 moment of inertia of the cross section and at the same time being of such nature as to resist more effectively such compression strains by virtue of the greater cross sectional area of the compression resisting material.

30 A still further object is to devise a cement reinforced steel trussed structure that can be readily constructed and which will be comparatively light in weight for its size and strength.

35 Another object is to devise a trussed structure which will lend itself to being nested during manufacture, transportation and storage, and yet another object is to devise a structure in which several units can 40 be built up into a complete trussed structure either during manufacture or erection.

My invention consists of a cement reinforced steel structure constructed and arranged all as hereinafter more particularly 45 described and illustrated in the accompanying drawing in which:

Fig. 1 represents a front elevational view of my preferred construction, showing the same in the form of a pole.

50 Fig. 2 is a side elevation thereof.

Fig. 3 is a cross sectional view taken on the line 3—3 Figure 1.

Fig. 4 is an enlarged cross sectional view on the line 4—4 Figure 1.

55 Like characters of reference indicate corresponding parts in the different views.

1 are the longitudinal steel members of the structure, each consisting preferably of a plurality of spaced apart steel rod members disposed as is shown in the cross sectional views and of sufficient strength to take care of the tensile stresses required, when taken together with the relatively small longitudinally extending auxiliary steel members 2 which surround the members 1 and are adapted to retain the cement filler 3 in position, it being understood that the steel members 1 and 2 are embedded in Portland cement or other cementitious material of the requisite consistency to reinforce them under compression strains. The independent longitudinal members 1 and the auxiliary members 2 which preferably consist of wire mesh and the cement filler 3 are tied together by means of suitably spaced lateral steel members 4, which are embedded or encased in the lateral cement members 5.

The cement portion of the unit structure is preferably cast about the members 1, 2 and 4 so that the lateral cement members 5 will be homogeneously united to the cement fillers 3.

In the form of pole illustrated, the unit is of substantially V-shaped cross section, 85 being provided with opposed longitudinal flange portions 6. Reinforcing cement ribs 7 encasing steel reinforcing and tying members 8 are provided for increasing the 90 resistance against distortion at the junction of the flange members with the legs of the V-shaped portion.

9 are cross straps constructed of metal or cementitious material, either reinforced or not as the case may be, said straps extending 95 across the opposite faces of the flanges 6 to the faces provided with the ribs 7 and adapted to be secured to such flanges by means of the bolts 10 which extend therethrough.

The straps 9 are provided for preventing the distortion of the legs of the pole due to excessive spreading stresses.

The straps 9 are not applied to the pole until the same is about to be erected, and consequently my poles, which are of V-shaped cross section, will nest together during storage or transportation, as indicated in dotted lines in Figure 3.

Where desired, two of my poles of V-shaped cross section can be erected in opposed relation to one another and joined to-

gether by lateral members, thus making up a much stronger structure. Used singly, they are particularly applicable for use as trolley or electric light poles.

- 5 They are in fact reinforced steel structures in which the reinforcement is cementitious material such as Portland cement. The principle involved is entirely distinct from reinforced cement structures in which 10 the reinforcing steel is provided for reinforcing the cement against tensile stresses whereas in my structures the cement is provided for reinforcing the steel against compressive strains, which experience has shown 15 to be the limiting strain in the design of steel truss poles or tower structures.

It is particularly noticeable by all engineers using steel trussed poles and towers that such structures are relatively weak in 20 the members subjected to compressive strains due to the tendency to deform or buckle under stresses substantially less than tensile stresses which such members resist.

A pole constructed according to my invention overcomes this difficulty by the use of 25 a plurality of independent members tied together by suitably disposed transverse members, each member as above stated comprising longitudinally disposed steel members which are provided with compression 30 reinforcement of cementitious material such as Portland cement.

The complete pole whether in the case of 35 unit construction or built up form is capable of resisting compressive strains better than a steel structure of equal steel cross sectional area and further, such a pole will be substantially equal in weight to a structure composed solely of steel of the same 40 strength and will be much lighter than a reinforced concrete pole of the same size and strength. It will moreover lend itself much more readily to being transported due to its light weight and adaptability to nesting, as 45 well as effecting a considerable saving in material and labour in construction.

In providing the ribs 7, I do so to increase the resistance of the angle portions to lateral stresses which might tend to spread 50 the flanges 6. This is particularly desirable as a means for resisting the ground pressure upon the outwardly extending flanges 6 in the case of a pole embedded in the soil and subjected to lateral strains.

55 On referring to the drawing, it will be noted that the transverse members 5 are of deep cross section below the ground line of the poles in order to act as ground anchors for lateral stresses.

60 What I claim as my invention is:

1. A cement reinforced steel structure comprising independent longitudinal steel members, suitably spaced transverse steel members connecting the respective longitudinal steel members together, said longitudi-

dinal and transverse members encased in cementitious material, opposed longitudinal flanges on the sides of the structure, and tieing means extending between the opposed flanges.

2. A cement reinforced steel structure comprising independent longitudinal steel members, suitably spaced transverse steel members connecting the respective longitudinal steel members together, said longitudinal and transverse members encased in cementitious material, opposed longitudinal flanges on the sides of the structure, and transverse straps extending between the opposed flanges and secured thereto.

3. A cement reinforced steel structure comprising independent longitudinal steel members, suitably spaced transverse steel members connecting the respective longitudinal steel members together, said longitudinal and transverse members encased in cementitious material, opposed longitudinal flanges on the sides of the structure, and reinforcing means between the flanges and main portion of the structure for reinforcing the junction of the flanges and the main portion against fracture or distortion.

4. A cement reinforced steel structure comprising independent longitudinal steel members, suitably spaced transverse steel members connecting the respective longitudinal steel members together, said longitudinal and transverse members encased in cementitious material, opposed longitudinal flanges on the sides of the structure, laterally extending spaced ribs of cementitious material between the flanges and the main portion of the structure, and reinforcing and tieing metal members in the ribs secured at their ends to the longitudinal steel members.

5. A cement reinforced steel structure comprising independent longitudinal steel members, suitably spaced transverse steel members connecting the respective longitudinal steel members together, said longitudinal and transverse members encased in cementitious material, and opposed longitudinal flanges on the sides of the structure, the structure being V-shape in cross section for enabling one structure to be nested within another.

6. A cement reinforced steel structure comprising independent longitudinal steel members, suitably spaced transverse steel members connecting the respective longitudinal steel members together, said longitudinal and transverse members encased in cementitious material, and opposed longitudinal flanges on the sides of the structure, the structure being V-shape in cross section for enabling one structure to be nested within another, and the main portion of the structure between transverse members having orifices extending through the cementitious material.

7. A cement reinforced steel structure comprising independent longitudinal steel members, suitably spaced transverse steel members connecting the respective longitudinal steel members together, said longitudinal and transverse members encased in cementitious material, the longitudinal members arranged so that when encased in the cementitious material the resultant structure will be V-shape in cross section ¹⁰ with orifices extending through the legs of the structure between the spaced transverse members.

JOHN GRANT JACKSON.
